FORMING DIES

Charles W. Pedersen, New York, N. Y.

Application June 2, 1953, Serial No. 359,237

2 Claims. (Cl. 153—48)

(Granted under Title 35, U. S. Code (1952), sec. 266)

The invention described herein may be manufactured and used by or for the Government of the United States of America for governmental purposes without the payment of any royalties thereon or therefor.

This invention relates to forming dies and more particularly to forming dies of the type including a plurality of separable, adjacent, forming sections assembled according to a predetermined pattern.

In the formation of cable straps, pipe straps or the like it has been known for some time that a die made from preformed sections assembled side-by-side has a tremendous advantage over unitary dies. The term "unitary dies" as used in this disclosure is defined as a combination of male and female portions of dies wherein each portion is an integral unit. Unitary dies are very expensive. Where the number specimens of any one particular product to be formed by the unitary dies is relatively small the cost per unit specimen of the product adapted to be formed by the unitary dies is unreasonably high. This inherent disadvantage of unitary dies, per se, is emphasized where the dies are used to form a work-piece of strip stock into a series of predetermined adjacent curvatures and the dimensions and configurations of each curvature repeats frequently. For example, in shipbuilding it is necessary to create a large variety of straps for supporting cables, pipes or the like. The variety of straps stems from combinations of such varieties as the number of pipes or cables supported by the straps, their diameters, the arrangement, etc. Throughout a vessel various combinations of number and size of parallel runs of cable and pipe come together and require a variety of straps, the variety being equal in number to the combinations, for supporting the cables, pipes or the like. It is a known expedient to form these straps out of strip stock by means of forming dies that are assembled from sections of various shapes and sizes which sections are pre-formed to correspond to particular diameters of cable or pipe. For an example of this type of die, reference is made to U. S. Patent 1,336,388.

A disadvantage in the use of the sectional dies known to the prior art is that no provision is made for forming straps, or the like, which are adapted to secure the smallest and largest cable and/or pipe side-by-side. Another marked disadvantage is that more time is required in assembling and disassembling the sections of dies known to the prior art since each section is not symmetrical.

This invention marks a departure from the prior art by providing a die adapted to be assembled in a power press from a plurality of sections. Furthermore the process of assembling the die requires minimum training and a minimum of setup time as compared to similar devices known to the prior art. This invention is characterized by a marked degree of versatility in operation.

An object of this invention is to provide a forming die.

A further object is to provide a forming die of a plurality of separable sections.

2

A further object is to provide a forming die of a plurality of separable sections and indent spaces.

A further object is to provide a forming die of a plurality of sections that can be selectively assembled 5 in any combination of sizes of adjacent sections.

A further object is to provide a sectional forming die for straps or the like.

A further object is to provide a sectional forming die for forming straps which are adapted to secure any combination of sizes of adjacent cables and/or pipes or the like.

Other objects and many of the attendant advantages of this invention will be readily appreciated as the same becomes better understood by reference to the following 15 detailed description when considered in connection with the accompanying drawings wherein:

Fig. 1 is a fragmentary view of the assembled die in a power press, and

Fig. 2 is a pictorial view of one upper die section, one lower die section, and one indent spacer in operative relationship.

The embodiment of the forming of the invention disclosed in Figs. 1 and 2 is designed for use in a power press having a ram a fragment of which is shown at 12 and a bed a fragment of which is shown at 14. A forming die 16 mounted in the ram 12 and the bed 14 of the power press is shown in operative relationship with a work-piece 18 formed into a cable strap by the die 16. The workpiece 18 having been formed into a cable strap is adapted to support a relatively large cable and a pair of smaller size cables of equal diameter. The forming die 16 includes an upper forming die portion or male die portion 22 and a lower forming die portion 24 and adapted to mate with the male die portion 22. Each of the die portions 22 and 24 is an assembly of a plurality of separable, similar sections such as 26, 28 and 32 mounted in the ram 12 of the power press, not shown, and a corresponding plurality of sections 34, 36 and 38 mounted on the bed 14 of the power press. The lower forming die portion 24 is stationary while the upper forming die portion 22, secured in the ram 12 of the power press, is reciprocated into and out of mating relationship with the lower die portion 24. Indent spacers 42, 44, 46, and 48 are included between each pair of sections of the lower forming die portion 24.

In Fig. 2 one section 52 designed for use as part of the upper forming die 22, a corresponding section 54 designed for use as part of the lower forming die 24, plus one indent spacer 56 are shown in operative relationship but removed from the power press and not including a work-piece between the sections. The section 52 of the upper forming die has uniform thickness along the width thereof. The top of the section 52 terminates in a dovetail 58. The dovetail 58 of the section 52 is adapted to slidably engage within a continuous dovetail slot or channel in the ram 12. The lower part of the section 52 is substantially rectangular in cross section terminating in a semicircular working surface of radius R. The thickness of the section 52 is equal to 2R. The width of the section 52 which is equal to the width of section 54 is determined by the width of the stock used for workpiece 18.

The thickness of the section 54 is reduced from a thickness equal to that of the section 52 by being recessed 65 equally at 62 and 64. The section 52 is formed with a pair of aligning openings 66 and 68 on one side and a pair of corresponding aligning studs only one of which is shown at 72 in Fig. 1. The aligning openings 66 and 68 and the aligning studs 72 facilitate the rapid assembly of the sections included in the lower die portion 24. Seated on the shoulder 74 bordering the recess at 62 is the indent spacer 56. When the sections 34, 36 and 38 included in

the lower forming die portion 24 of Fig. 1 are assembled, the indent spacers 42, 44, 46, and 48 slide into the channel defined by the recesses in the adjacent sections of the lower die portion 24.

The indent spacers such as 56 of Fig. 2 are substantially rectangular in cross section terminating in a semicircular working surface 76. All of the indent spacers are formed to have the same width and consequently the same radius of working surface. The indent spacers serve to indent the workpiece 18 as at 82 and 84 to permit the strap to properly separately support each of the cables, pipes, or the like.

The procedure to be followed in designing the separate sections 52 and 54 of the upper and lower die portions 22 and 24, respectively, involve first selecting each size of bar stock having a thickness which is equal to the diameter of the cable, pipe, or the like to be supported by the corresponding portion of the strap formed by the die including these sections. The dovetail 58 on the section 52 is of a uniform size which is prescribed for each of the sections adapted to be included in the upper forming die portion 22 for use in a particular power press. The sections 52 and 54 are positioned in Fig. 2 in the same spaced relationship they occupy when mounted in a power press with the ram 12 at the lower limit of its stroke. The spread G between the ram 12 and the bed 14 when the ram 12 is at the lower limit of its stroke defines the distance between the upper surface of the working portion of the section 52 and the bottom surface of the section 54. The depth of the recesses at 62 and at 64 are equal to each other and to the depth of the recesses in the other sections. The depth of each recess is half the thickness of the indent spaces. The thickness of indent spaces 56 is based on a compromise between strength of the spaces on the one hand and well-defined indents on the other hand. For example if the indent spacer 56 were made too thin its effective life would be very short, whereas if it were too thick it could not define an indent unless the cables were separated. Considerable success has been achieved in making the indent spacers $\frac{3}{16}$ of an inch thick when using stock $\frac{3}{32}$ of an inch thick for the straps. Let it be assumed for the purposes of the immediate discussion that the thickness of the stock used in forming the straps is $\frac{3}{32}$ of an inch thick. The dimension A therefore represents the summation of the radius R of the cable for which the strap is being formed plus the thickness of the stock which is $\frac{3}{32}$ of an inch plus the radius of the working surface 76 of the indent spacer 56 which is likewise $\frac{3}{32}$ of an inch. The base of the triangle of which A is the hypotenuse is equal to R since it is equal to half the thickness of the upper section 52. By means of the Pythagorean Theorem the magnitude of C is readily determined. If the strap is for cable the distance D may be arbitrarily chosen to be $\frac{1}{32}$ of an inch less than the diameter of the cable for which the strap is being formed, in order to permit the strap to clamp the cable. The distance F is arbitrarily fixed; for one power press for which it has been designed the distance F has been fixed at one inch. Therefore by subtracting the sum of D, C, and F from G the distance represented by E is readily determined. Once the distance defined by E is determined sufficient information is available for forming the indent spacer 56.

To determine the height of the lower section 54 a corresponding series of computations are resorted to as has been described in connection with the computations for determination of the dimensions of the indent spacer 56. The top of the section 54 is channeled at 86 thereby providing a pair of opposed rims 88 and 92. The rims 82 and 92 terminate in a semicircular working surface the radius of which has been chosen based upon compromised considerations similar to those involved in designing the indent spacer 56 at $\frac{3}{32}$ of an inch. The depth of the channel at 86 is derived after the height of the section

54 is determined by means of computations similar to those outlined in connection with the determination of the dimensions of the indent spacer 56. Though the surface of the channel at 86 is indicated as a flat surface it can take the shape of any tool which is conveniently available. The limitation to be kept in mind is that sufficient clearance needs to be provided between the working surface of the upper section 52 and the surface 86. Where the only consideration is that of clearance it is evident from an examination of the sections 36 and 38 of the lower forming die 24 that the depth of the channel is not the same. The depth of the channel in a section such as 38 corresponding to a cable of larger diameter is deeper than that in the section such as 36. However if this clearance is made uniform it is possible to introduce an additional safety factor for preventing unnecessary damage to the die sections.

With the clearance the same and with the ram 12 withdrawn to the upper limit of its stroke a gauging means such as a strip of metal cut to an exact length can be used to check whether the corresponding upper and lower sections of the die portions 22 and 24 are correctly selected. In explanation let it be assumed that several power presses in one immediate vicinity are used for forming cable straps. Let it further be assumed that the spread G is not identical for all of the power presses. Where the dovetail 58 is the same for all the machines it is possible to take an upper section 52 that is designed for use with a particular power press having one spread G and assembling it in another power press having a different spread G. It is evident that the section 52 will either be too short if the spread is greater or it will strike the corresponding lower section 54 if the spread is smaller. Results in either case are clearly undesirable. By making the clearance the same between the working surface of the section 52 and the surface 86 of the channel the section 54 a gauge may be used as a means of checking against such an eventuality.

In operation the sections 52 and 54 are assembled in the ram 12 and the bed 14 of the power press according to the desired design of cable strap. Block 94 having aligning pins and aligning openings similar to those at 66, 68, and 72 is engaged with the stop, not shown, secured to the bed 14 of the power press. Subsequently the sections 34, 36 and 38 are sequentially positioned on the bed 14. And end block 96 corresponding to the end block 94 is the last element included in the lower die portion 24 to be assembled on the bed 14 of the power press. All of the elements are clamped against the previously mentioned stop, not shown, by means conventionally associated with power presses for like purposes. The upper die portion 22 is then assembled by first inserting the end block 98 into the dovetailed channel 102 extending transversely of the ram. The end block 98 bears against a stop, not shown, which has been previously aligned in cooperative relationship to the stop on the bed 14, both of which are not shown, and cooperates with the end block 94 to define the attaching ends of the cable strap. The sections 26, 28, and 32 correspond to and are adapted to be brought into operative association with the sections 34, 36, and 38. They are readily assembled in the channel 102 of the ram 12. An end block 104 corresponding to the end block 98 constitutes the last element of the upper die portion 22 assembled in the ram 12. A clamping means, not shown, secures the sections included in the upper die portion 22 to the ram 12.

To provide an additional safety factor to insure the proper order of assembly of the several sections included in each of the die portions 22 and 24 a tool, not shown, having a portion which is of substantially the same thickness as that of the indent spacers and having an upwardly projecting portion terminating in a knifelike edge may be used to indicate whether the width of the upper sections correspond to the width of the lower sections of the die. When the tool is inserted in the position normally occu-

pied by the indent spacers its knife edge should align with the abutting surfaces of adjacent upper die sections.

Not all of the indent spacers act on the workpiece 18 during the forming operation. For example, in Fig. 1 the indent spacers 42, 46, and 48 appear to serve no useful purpose. However in practice it has been found that though they do not operate directly on the workpiece 18 they serve as strengthening members preventing damage to the lower die sections.

In order to quickly identify the multiplicity of various sections for the upper die portion 22 and the lower die portion 24 each section may be stamped, stencilled, or otherwise marked with the diameter of the cable of pipe size for which it is designed. The indent spacers are correspondingly stamped. For example the upper section 54 and the indent spacer as shown in Fig. 2 would bear the same identification marks. If desired the identification of the particular power press for which the sections have been designed can likewise be stamped on each of the sections. This is particularly advantageous where a large number of power presses located in the same immediate vicinity are used for forming straps as described herein.

Where adjacent sections of the lower die portion 24 are not the same size such as 36 and 38 in Fig. 1, the indent spacer 46 that is used is the one that is designed to correspond to the section 38 for the larger diameter cable. The reason for this can be appreciated if one pictures what will happen if the indent spacer 44 is used in place of the indent spacer 46. Where it is desired to provide straps that are to be secured to supporting structure through intermediate spacer pads it is only necessary to vary the height of the end blocks 94, 98, 96 and 104. For example by decreasing the height of the end block 98 it is possible to secure the corresponding end of the cable strap formed thereby to associated supporting structure through spacer pads.

Absolutely no guess work or personal judgment is involved in assembling the various elements comprising the die 16. If a chart is provided to the machine operator indicating the sizes of the adjacent pipes and/or cables to be secured by the cable strap the machine operator simply uses the sections of the die having the corresponding markings. The entire assembly or disassembly of the die 16 can be accomplished with ease in a few minutes. Checking by means of the two gauging tools previously described need take no longer than ten seconds. One of the salient advantages of this die arrangement lies in its versatility. There is substantially no limitation upon the sizes of immediately adjacent sections of the die. A very large section of the die can be assembled immediately adjacent to a very small section of the die for clamping a very large cable immediately adjacent to a very small cable. Other advantages of this die over similar devices known to the prior art lies in the fact

that the sections of the die as described herein may be readily mass produced, thereby reaping all the advantages of low cost, accuracy, availability, etc.

Obviously many modifications and variations of the present invention are possible in the light of the above teachings. It is therefore to be understood that within the scope of the appended claims the invention may be practiced otherwise than as specifically described.

I claim:

- 10 1. A forming die comprising a male die portion and a mating female die portion, said male portion including a plurality of forming sections each terminating in an arcuate forming surface, whereby any combination of sizes of adjacent sections may be arranged in said male die portion, said female die portion including a corresponding plurality of sections, each female die portion including a pair of rims at the opposed margins thereof, said rims being rounded and serving as forming surfaces, each adjacent pair of sections in said female die portion being 15 jointly recessed to define a channel, an indent spacer terminating at one end in a rounded working surface for each channel.
- 20 2. A forming die comprising a male die portion and a mating female die portion, said male die portion including a plurality of contiguous separable forming sections, each of which terminates in an arcuate forming surface, the forming sections of said male die portion are adapted to have their combined forming surfaces in discontinuous contact with a workpiece, said female die portion including a corresponding plurality of separable sections, each section of said female die portion being formed with a pair of opposed rounded rims defining spaced working surfaces, the transverse dimension of each section of said female die portion at said rims being smaller than 25 the transverse dimension of the corresponding section of the male die whereby adjacent sections of said female die define a channel therebetween, an indent spacer having a rounded edge in each channel, each indent spacer adapted for indenting a workpiece and also strengthening the rims 30 of the sections of the female die portion whereby the die may include any combination of sizes of adjacent sections.
- 35 30
- 40 35
